RING JOINT GRINDING MECHANISM

Edgar A. Smith, Huntington, Oreg.

Application October 23, 1945, Serial No. 623,987

3 Claims. (Cl. 51—26)

1

This invention relates to a grinding mechanism, and more particularly to a mechanism for grinding ring joints.

An object of this invention is to provide an improved ring joint grinder having a power drive and being adjustable for different size rings and joints.

Another object of this invention is to provide a ring joint grinding mechanism which is adapted for power grinding of ring joints around holes in boilers and the like, and which is held in position by anchor legs.

It is a further object of this invention to provide for an improved grinding mechanism for ring joints having means for holding different size rings and means for applying yielding pressure during grinding to produce even pressure at all times.

Other objects of this invention will appear from the following specification and claims and from the accompanying drawing illustrating the invention, wherein:

Figure 1 is an elevational view, partly in section, showing the mechanism in operative position;

Figure 2 is a detail plan view of the frame top plate showing slots for adjusting the anchor legs;

Figure 3 is a detail plan view of the rotary upper plate showing holes for adjustment; and

Figure 4 is a detail plan view of the lower spreader plate showing notches for the expanding leg members.

Figure 5 is a detail fragmentary sectional view through the anchor plate showing the notches in the leg members.

Referring to the drawing, the anchor frame denoted generally by the numeral 1 has two anchor legs 2 having inwardly extending flanges 3 at the top and outwardly extending flanges 4 at the bottom. A top plate 5, supported by flanges 3 connect the legs 2 together. The top plate 5 has slots 6 therein, and bolts 7 pass through the slots 6 and holes in the flanges 3 to hold the anchor frame together. The slots 6 provide for adjustment of the spacing between the legs 2 depending on the size of the joint to be ground. Apertures in the lower flanges 4 provide for bolts or studs 8 for anchoring the frame 1 over the joint to be ground in a boiler or pipe 9. The anchor frame 1 may thus be bolted to the side of a boiler or to a pipe flange.

A drive shaft 10 having a drive fitting 11 at the top for connection to any suitable power source passes through an aperture 12 in the center of anchor plate 5. The lower portion of shaft

2

10 is threaded, as at 13, and the shaft 10 is provided with nuts 14 and 15 for anchoring a top plate 16 in fixed position, and a nut 17 for supporting a bottom spreader plate 18 in adjustable position. The periphery of the spreader plate is provided with three notches 19 for receiving three leg members 20, the tops of which are removably inserted in apertures 21 in the top plate 16. The tops of the leg members 20 are turned out as at 22 for better anchoring in the top plate 16. By turning nut 17, the spreader plate 18 may be raised or lowered to adjust the spreading of the leg members 20.

The lower ends of the leg members 20 are notched as at 23 for receiving a ring 24 which is to be ground in. Adjusting the position of the spreader plate 18 enables the leg members 20 to clamp different sizes of rings. A ring 25 is fixed to the drive shaft 10 above plate 16 by means of a set screw 26. The coil spring 27, positioned between the ring 25 and the frame plate 5, produces yielding downward pressure on the shaft which is transmitted to the leg members 20 wedged between upper plate 16 and spreader plate 18 and thereby to the ring 24 to be ground in. Thus even pressure will be applied to the ring 24. To insure the spring pressure being transmitted to the leg members 20, the leg members 20 may be notched where they enter holes 21 to form abutments engaging the lower surface of the plate 16. Each of the leg members 20, Figure 5, is provided with a notch 25.

In operation the ring 24 to be ground is placed around the notches 23 of the expanding leg members 20, the nut 17 is tightened to force spreader plate 18 up to expand the leg members 20 and cause the ring 24 to be clamped tightly and centered at the same time. The anchor legs 2 are then placed over the studs or bolts 8 around the hole in the boiler and anchored down. Grinding compound is then applied to the under surface of the ring 24 and power is applied to shaft 10 to rotate the plate 16 and the leg members 20 to grind in the ring 24. The mechanism is adapted for grinding both bevel and flat joints. The several apertures 21 enable selective placing of the leg members 20 to take different ring sizes.

It is evident that a simple device has been provided for grinding ring joints and which will result in a great saving of labor.

While a certain specific embodiment of this invention has been shown it will be understood that various modifications may be made within the spirit of the invention. Therefore no limitations on the invention are intended other than

are imposed by the scope of the appended claims.

I claim:

1. In a mechanism for grinding ring joints, an anchor frame embodying a pair of upstanding legs spaced from each other, a horizontally disposed plate resting upon the top ends of said legs and connected to the latter, there being a centrally disposed opening extending through said plate, means on the lower ends of said legs for connecting same over a joint to be ground, a drive shaft extending through the centrally disposed opening in said plate and having one end projecting beyond the face of said plate and the other end projecting beyond the opposite face of said plate, the other end of said shaft being threaded for a portion of its length, said threaded portion extending from the free edge of the other end of said shaft and terminating at a point substantially midway of the latter, an anchor plate provided with a plurality of radially disposed groups of spaced openings mounted on said shaft and fixedly secured thereto adjacent the termination point of its threaded portion, a spreader plate provided with a plurality of spaced peripheral notches on said shaft adjacent the free edge of said other end and mounted for slidable longitudinal movement therealong, a plurality of vertically disposed leg members spaced from each other and connected to said anchor and spreader plates, the upper end of each of said leg members extending through an opening of each of the radially disposed groups of spaced openings in said anchor plate, each of said leg members being in embracing relation with a complementary peripheral notch in said spreader plate, the lower end of each of said leg members being provided with means for the reception of a ring to be held thereby, and means on said shaft in association with said spreader plate for slidably moving the latter longitudinally upwardly and downwardly along the shaft to thereby increase and decrease the spreading of said leg members.

2. In a mechanism for grinding ring joints, an anchor frame embodying a pair of upstanding legs spaced from each other, a horizontally disposed plate resting upon the top ends of said legs and connected to the latter, there being a centrally disposed opening extending through said plate, means on the lower ends of said legs for connecting same over a joint to be ground, a drive shaft extending through the centrally disposed opening in said plate and having one end projecting beyond the face of said plate and the other end projecting beyond the opposite face of said plate, the other end of said shaft being threaded for a portion of its length, said threaded portion extending from the free edge of the other end of said shaft and terminating at a point substantially midway of the latter, an anchor plate provided with a plurality of radially disposed groups of spaced openings mounted on said shaft and fixedly secured thereto adjacent the termination point of its threaded portion, a spreader plate provided with a plurality of spaced peripheral notches on said shaft adjacent the free edge of said other end and mounted for slidable longitudinal movement therealong, a plurality of vertically disposed leg members spaced from each other and connected to said anchor and spreader

plates, the upper ends of each of said leg members extending through an opening of each of the radially disposed groups of spaced openings in said anchor plate, each of said leg members being in embracing relation with a complementary peripheral notch in said spreader plate, the lower ends of each of said leg members being provided with means for the reception of a ring to be held thereby, means on said shaft in association with said spreader plate for slidably moving the latter longitudinally upwardly and downwardly along the shaft to thereby increase and decrease the spreading of said leg members, and a resilient means on said shaft for yieldably urging said leg members downwardly.

3. In a mechanism for grinding ring joints, an anchor frame embodying a pair of upstanding legs spaced from each other, a horizontally disposed plate resting upon the top ends of said legs and connected to the latter, there being a centrally disposed opening extending through said plate, means on the lower ends of said legs for connecting same over a joint to be ground, a drive shaft extending through the centrally disposed opening in said plate and having one end projecting beyond the face of said plate and the other end projecting beyond the opposite face of said plate, the other end of said shaft being threaded for a portion of its length, said threaded portion extending from the free edge of the other end of said shaft and terminating at a point substantially midway of the latter, an anchor plate provided with a plurality of radially disposed groups of spaced openings mounted on said shaft and fixedly secured thereto adjacent the termination point of its threaded portion, a spreader plate provided with a plurality of spaced peripheral notches on said shaft adjacent the free edge of said other end and mounted for slidable longitudinal movement therealong, a plurality of vertically disposed leg members spaced from each other and connected to said anchor and spreader plates, the upper end of each of said leg members extending through an opening of each of the radially disposed groups of spaced openings in said anchor plate, each of said leg members being in embracing relation with a complementary peripheral notch in said spreader plate, the lower end of each of said leg members being provided with means for the reception of a ring to be held thereby, rotatable means embodying a threaded member on said shaft in association with said spreader plate for slidably moving the latter longitudinally upwardly and downwardly along the shaft to thereby increase and decrease the spreading of said leg members, and a coil spring operatively connected to said shaft for yieldably urging said leg members downwardly.
